UNITED STATES PATENT OFFICE.

HENRY L. FULENWIDER, SAMUEL C. BOND, AND WILLIAM G. BOND, OF WILMINGTON, DELAWARE, ASSIGNORS TO NATIONAL CORK AND SEAL COMPANY, OF WILMINGTON, DELAWARE, A CORPORATION OF DELAWARE.

METHOD OF CAPPING BOTTLES.

No. 852,323.

Specification of Letters Patent.

Patented April 30, 1907.

Application filed August 13, 1906. Serial No. 330,449.

To all whom it may concern:

Be it known that we, HENRY L. FULENWIDER, SAMUEL C. BOND, and WILLIAM G. BOND, residing at Wilmington, in the county 5 of Newcastle and State of Delaware, citizens of the United States, have invented or discovered certain new and useful Improvements in Methods of Capping Bottles, of which improvements the following is a specification.

The invention described herein relates to an improved method in securing sealing caps on bottles. These caps are provided with a packing generally consisting of disks formed 15 of a yielding material such as cork, which will not be affected by the contents of the bottle. It has been the practice in applying these caps to the bottle to press the cap toward the bottle with sufficient force to cause 20 the disk to seat hermetically in the end of the bottle neck. The flanges of the cap are then bent inwardly under the rib or bead on the bottle. If in thus bending the flanges inwardly care is not taken to prevent a bulging 25 or folding of the flange, the pressure of the gases in the bottle will be sufficient to force the disk from its seat, the straightening of the bulge or fold in the flange permitting an unseating movement of the disk. Even in no 30 fold or bulge is formed in the cap flange, a shrinkage or contraction of the disk in the cap would permit the escape of gases from the bottle.

It is the object of this invention to subject 35 the metal of the cap when applying to the bottle, to stretching within the limits of elasticity so that the packing disk will be subjected at all times to a seating pressure. In thus subjecting the metal of the cap to tension, all possibility of forming folds or bulges 40 is avoided, and any shrinkage or contraction of the packing disk will be compensated for. The invention is hereinafter more fully described and claimed.

45 In the accompanying drawings forming a part of this specification, Figure 1 is a sectional elevation of a portion of a machine adapted to the practice of our invention; Figs. 2, 3 & 4 are views showing the parts of 50 the machine directly operative to secure the cap on the bottle, at different stages of the

operation; Figs. 5, 6, and 7 are sectional views, illustrating another form of apparatus for carrying out our improved method.

In the practice of our invention the top of 55 the cap is preferably made flat as shown in Figs. 2 and 5 and the portion of the presser head 23 in Fig. 2 or 5 in Fig. 5 operative on the cap is so shaped that when pressing the cap on the bottle, it will have an outward 60 stretching action on the top of the cap and will tend to force the outer edge of the top of the cap downwardly around the lip of the bottle. This result is produced when using caps with flat tops by making the face of the 65 presser head 23 concave and of such a diameter relative to that of the caps, that the edge a of the head will bear on the cap closely adjacent to the periphery of the top thereof slightly before or in advance of the end of its 70 cap seating movement.

After the cap has been forced down over the end of the bottle neck, seating the packing disk hermetically and stretched or placed under tension, the tools or parts designed to 75 act on the flange of the cap, are brought into operation. These tools or parts, i. e., the spinning rollers 21 of the construction shown in Figs. 1 to 4 and the wiping fingers 11 of the construction shown in Figs. 5 to 7, are so 80 shifted during the seating of the cap that when the cap is seated, they will bear upon the flange in or approximately in a plane indicated by the line y—y passing through the apex of the rib or bead b of the bottle. 85 These tools are now caused to move down along and under the bead b bearing at all times with sufficient force on the flange to cause it to bear smoothly on the bead but also to subject it to sufficient tension to produce a stretching of the metal within the limits of elasticity. This pull along the flange is a continuation of the radial pull effected by the presser heads in seating the packing disk so that practically the whole 90 cap is stretched and the metal placed under tension so that when the cap is anchored by the bending of the edges of the flange under the bead b, the cap will exert a constant seating pull on the packing disk. 95 While we do not limit ourselves to any 100 particular form or construction of apparatus

for the practice of our improved method, we have shown two desirable forms of machine for that purpose. The construction shown in Figs. 1 to 4, inclusive, forms the subject 5 matter of an application filed December 22, 1905, Serial No. 292,949, and consists as stated in said application of a head A carried by a sleeve 12^a, movable in tubular standard 13^a. This head is yieldingly supported by a 10 spring 14^a, and suitable means are employed for moving down the head and the parts carried thereby, said means operating through the sleeve 9^a, all as described and shown in said application. The head carries a holding 15 rod, 18, which is surrounded by sleeves 19 and 20. One of these sleeves carries the spinning rollers and the other has mounted thereon means for shifting said spinning rollers into operative position as regards the cap to be 20 secured to the bottle. The sleeves, 19 and 20, are rotated by gear wheel 16 through a pinion 17, the gear wheel being rotated by the shaft 6^a. The movement of the sleeve 19 for forcing the spinning rollers 21 inward 25 is effected by a lever 27, adapted to be shifted by a cam 29 carried by the wheel 16, and the sleeve 20 by a cam ring 33, also carried by the wheel 16. The presser head 23 is yieldingly mounted in the holding rod 18, 30 and when forced down upon the bottle it takes a firm seat against the holding rod, as shown in Fig. 3. During the operation of securing a cap on a bottle, the presser head first operates as heretofore stated to stretch 35 the metal of the top of the cap radially and hold it in such stretched condition until the flanges have been anchored under the bead, b, of the bottle neck. As soon as the cap has been firmly seated the rollers having attained a position shown in Fig. 3 bear upon 40 the cap in or approximately in the plane of the line y—y, passing through the apex of the bead b. During the operation of capping, the rollers are carried rapidly around the 45 presser head and the cap on the bottle, and after having attained the desired bearing on the cap, as stated, a further downward movement along the flange and inward under the bead is given to the rollers, so that 50 they will spin the metal in against and under the bead of the bottle and exert a stretching action which as heretofore stated is a continuation of the stretching action produced by the presser head on the top of 55 the cap.

The construction shown in Figs. 5 to 7, inclusive, forms the subject-matter of an application filed August 20th, 1906, Serial No. 331,305. In this construction as stated in 60 said application, the head 1 is moved downward, so that the conical recess in its lower end will pass over the top of a bottle, and the presser block 5 bears upon the top of the cap as heretofore described, so as to effect a ra-

dial stretching of the metal of the top. By 65 the continued movement of the stem 4, the plunger 2 is moved down, compressing the spring 8 and causing the fingers 11 to move inwardly and also to turn toward a horizontal position, until the portions operative on 70 the flange of the cap bear upon such flange in the plane indicated by the line y—y passing through the apex of the bead b. Thereafter the plunger and head 1 move down together, the plunger having a slight downward movement independent of the head, so that the fingers or tools 11 will have a wiping movement along the flange of the cap, pressing it down and along under the bead b. This 75 stretching movement is a prolongation of the 80 stretching action produced on the top of the cap by the presser head 5, and places the metal of the cap under such a tension that when the cap is anchored by the bending of the edges of the flange under the bead, there 85 will be a constant seating pull on the packing disk in the cap. It is characteristic of both 90 the spinning operation effected by the machine shown in Figs. 1 to 4 and the wiping action effected by the construction shown in 95 Figs. 5 to 7, that the metal of the cap is smoothly and evenly applied to the bottle, and also placed as described under such a tension within the elastic limits of the metal 100 that there is a constant seating pull exerted by the metal so that any contraction or shrinkage of the packing disk will be immediately compensated for, and the hermetic seal of the bottle preserved intact.

It will be observed that our improved 100 method can be employed either with caps having a bead between the flange and top as shown in Figs. 2, 3, 4, or with a cap having a straight flange extending from the top as 105 shown in Figs. 5, 6, and 7.

It will be readily understood by those skilled in the art that our improved method of sealing bottles can be carried out by forms or constructions of machines other than those shown and described herein.

We claim herein as our invention:

1. The method of applying flanged sealing caps to bottles, which consists in pressing the cap on the top of a bottle mouth, simultaneously forcing the peripheral edge of the top of the cap downwardly around the edge of the bottle mouth, and then stretching the flange of the cap down and into locking contact with the bead or locking shoulder on the bottle, whereby the periphery of the cap top and the depending flange are placed under strain or tension tending to exert a sealing pressure.

2. The method of applying flanged sealing caps to bottles which consists in pressing the cap on the top of the bottle, subjecting the metal of the top and flange of the cap to a stretching action within the limits of elas-

ticity and locking the edges of the flange to the bottle.

3. The method of applying flanged sealing caps to bottles which consists in pressing the cap on the top of the bottle, and simultaneously radially stretching the metal of the top of the cap, stretching the metal along the locking bead of the bottle and locking the edge of the flange under said bead.
- 10 4. The method of applying flanged sealing caps to bottles, which consists in pressing the cap on the top of the bottle, stretching the

metal of the cap flange down along the bottle and locking the flange to the head or locking shoulder of the bottle.

In testimony whereof, we have hereunto set our hands.

HENRY L. FULENWIDER.
